[57] CLAIM

The ornamental design for a household screen, as shown and described.

DESCRIPTION

FIG. 1 is a perspective view of a household screen showing my new design;

FIG. 2 is a top plan view thereof;

FIG. 3 is a bottom plan view thereof;

FIG. 4 is a front elevational view thereof;

FIG. 5 is a right side elevational view, the opposite side being a mirror image thereof;

FIG. 6 is a front elevational view of a second embodiment of the present invention;

FIG. 7 is a left side elevational view of the embodiment shown in FIG. 6, the opposite side being a mirror image thereof;

FIG. 8 is a front elevational view of a third embodiment of the present invention;

FIG. 9 is a side elevational view of the embodiment shown in FIG. 8, the opposite side being a mirror image thereof;

FIG. 10 is a top plan view of the embodiment shown in FIG. 8;

FIG. 11 is a bottom plan view of the embodiment shown in FIG. 8;

FIG. 12 is a front elevational view of a fourth embodiment of the present invention;

FIG. 13 is a side elevational view of the embodiment shown in FIG. 12, the opposite side being a mirror image thereof;

FIG. 14 is a top plan view of the embodiment shown in FIG. 12; and,

FIG. 15 is a bottom plan view of the embodiment shown in FIG. 12;

The top and bottom views for FIG. 6 are substantially like that shown in FIGS. 2 and 3 with the small round mirror removed from the center segment and the end segments reversed.

The rear views for FIGS. 1, 6, 8 and 12 are not part of the claimed design.
